UNITED STATES PATENT OFFICE.

JOHN BINDER AND EMILIO ALBERTI, OF NEW YORK, N. Y., ASSIGNEES TO INTERNATIONAL CORK COMPANY, OF BROOKLYN, NEW YORK, A CORPORATION OF NEW YORK.

FEEDING ATTACHMENT FOR CROWN-CORK-MAKING MACHINES.

Application filed May 2, 1916. Serial No. 94,885.

To all whom it may concern:

Be it known that we, JOHN BINDER and EMILIO ALBERTI, a subject of the King of Hungary and a citizen of the United States, 5 respectively, and residents of the city of New York, in the county of Kings and State of New York, have invented certain new and useful Improvements in Feeding Attachments for Crown-Cork-Making Machines, 10 of which the following is a specification.

The present invention relates to machines for manufacturing bottle-, jar-, can- and like closures of the cap variety, including those termed "crown corks." The invention 15 pertains more particularly to means for feeding the sealing disks of cork or similar material of the closures to the assembling devices of the machine.

In machines of this type a mass of sealing 20 disks is placed indiscriminately into a hopper, wherefrom they are fed into a tube that leads to the transporting means, which conveys the sealing disks, one after the other, to the assembling elements of the cap 25 making machines. While it has been found comparatively easy to cause the disks to pass toward the said tube, it has been found very difficult to lead them into the tube without clogging the inlet to the latter, and it has 30 been found almost impossible to stack the disks properly in said tube. The troubles arise mainly due to the fact that the sealing disks are very light in weight. Other difficulties have been experienced in these feeding devices for the reason that the disks 35 vary to some extent in their thicknesses and are apt to take a curved or bent shape when being prepared or treated before they are put upon the assembling machine.

40 The main object of the present invention is to provide a simple and efficient attachment for cap making machines, which automatically delivers the sealing disks from a mass to the assembling machine without regard to their thickness, weight and more or less curved shapes.

With these and other objects in view, which will more fully appear as the nature of the invention is better understood, the 50 same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

55

One of the many possible embodiments of the invention is illustrated in the accompanying drawings, in which:

Figure 1 is a central vertical section taken through a feeding attachment constructed 60 in accordance with the present invention; Fig. 2 is a top plan view thereof; Fig. 3 is a section taken on line 3—3 of Fig. 1 on a larger scale; Fig. 4 is a section taken on line 4—4 of Fig. 1, also on a larger scale; Fig. 70 5 is a section taken on line 5—5 of Fig. 1, also on a larger scale; Fig. 6 is a section 75 similar to Fig. 1 showing on a larger scale the top portion of the apparatus; and Fig. 7 is a section taken on line 7—7 of Fig. 6. 75

In the drawings, the numeral 10 indicates 80 a portion of the frame of a crown cork assembling machine, having upon its table portion 11 mounted an upwardly extending support 12, which carries a hopper 13, that 85 is in the case illustrated in the drawings of cylindrical shape, its lower portion 14 being conical to cause the disk therein to move toward its longitudinal center line. The bottom 15 of this hopper is made of a separate piece and is adapted, as will hereinafter appear, to be vibrated or oscillated. The bottom is slightly concave and provided, 90 preferably, in its center with a circular outlet 16, the diameter of which is slightly 90 larger than that of an individual sealing 95 disk. Upon the underface of the bottom is formed a downwardly projecting tubular extension 17, through which the disks are 100 discharged from the hopper. This extension, which constitutes the outlet of the hopper, is seated eccentrically in a bushing 18, the latter being rotatably mounted in a step bearing 19, that is suitably attached to the support 12. To reduce undue friction between the bushing and bearing, there are formed raceways 20 and 21 in the said bushing and bearing, respectively, and in these raceways run balls 22 in the well known manner. The bushing may be rotated in any 105 suitable manner from the main driving shaft of the assembling machine, for instance there may be mounted upon the bush-

ing a pulley 23, over which runs a belt 24, that runs also over a pulley 25, the latter being mounted upon a rotating shaft 26 of the assembling machine. Sheaves 27 guide the movement of said belt. In order to prevent the bottom 15 from rotating with the bushing, there is formed upon the under-face of said bottom a lug 28, carrying an anti-friction roller 29, which is seated in a radially extending recess 30, that is formed in an extension 31 of the support 12.

The tubular outlet 17 of the hopper bottom is in alignment with the flaring mouth 32 of a stationary substantially vertically extending tube 33, leading to the transporting means 34 of the machine, which conveys the sealing disks one after the other to the assembling mechanism. The tube 33 is held above the transporting mechanism by a standard 35, and is provided in its wall with longitudinal slots 36, permitting of the insertion of a pointed instrument for the purpose of properly arranging the disks therein, should by accident some of the same travel therein edgewise.

Upon the upper face of the bottom, and more particularly near its peripheral portion there are formed lugs 37, which serve to agitate the mass of sealing disks in the hopper. Lugs 38 are formed around the outlet of the bottom and serve a similar purpose. In order to prevent the whole mass of sealing disks from resting upon the bottom and from clogging the outlet thereof, there is held a substantial distance above the said bottom within the hopper an inverted substantially funnel-shaped member 39.

The hopper bottom is provided with perforations 40, having each a diameter that is smaller than that of a sealing disk. As the hopper bottom is oscillated or vibrated, broken disks and foreign matter are sifted out from the mass. To prevent such broken parts and foreign matter from falling upon the step-bearing, there is formed upon the tubular extension 17 a collar 41, covering the step-bearing.

Near the outlet of the tube 33 there is formed in the same a slot 42, in alignment with which is held upon the standard 35 a shiftable stop 43, that is adapted to be projected into the said tube so as to prevent disks therein from falling onto the transporting means 34. This mechanism is made use of if the assembling device gets out of order and it becomes necessary to stop the feeding of the disks thereto.

The operation of the device is as follows: A mass of sealing disks is placed indiscriminately into the hopper and rotation imparted to the bushing 18. Inasmuch as the tubular outlet of the hopper bottom is seated eccentrically in said bushing and a rotation of the hopper bottom is prevented, as above

described, the said bottom will be oscillated or vibrated, with the result that the disks therein in traversing the outlet of the bottom are caused to pass into the tubular extension thereof. As this tubular extension oscillates or vibrates above the flaring mouth of the tube 33, the disks will be discharged into the said tube. The continuous oscillation or vibration of the tubular extension 17 of the hopper bottom causes a proper stacking of the disks therein. No matter in what position they arrive in the tubular extension, they will be brought by the continuous vibrating motion, before they reach the flaring mouth of the tube 33, into substantially horizontal position and into exactly horizontal position as they pass into the stationary tube 33. A clogging of the outlet of the hopper is obviously impossible, due to the continuous motion of said bottom. The thickness and more or less curved shapes of the disks do not affect the proper operation of the device.

It is obvious that, while herein a specific means has been disclosed for vibrating or oscillating the hopper bottom, any other suitable means could be provided without departing from the invention, which lies mainly in vibrating the hopper bottom or that part thereof in which its outlet is formed for the purpose specified. Attention is called to the fact that, while herein the tubular extension 17 of the hopper bottom has been shown of considerable length, it may be dimensioned otherwise, care being taken so as not to make it too short, it having been found that the proper stacking of the disks depends mainly upon the time during which they are subjected to vibrating motion.

What we claim is:—

1. In a device of the character described, the combination with a hopper having a bottom provided with a tubular outlet and carrying lugs upon its upper face, of a stationary tube leading from said outlet and provided with a mouth having a diameter larger than that of said outlet, and means for vibrating said bottom and outlet in relation to said tube.

2. In a device of the character described, the combination with a hopper having a tubular outlet, of a stationary tube leading from said outlet and provided with a mouth having a diameter larger than that of said outlet, means for vibrating said tubular outlet in relation to said tube, and an inverted substantially funnel-shaped member disposed within said hopper a substantial distance above said outlet.

3. In a device of the character described, the combination with a hopper having a bottom provided with a tubular outlet, of a stationary tube leading from said outlet and provided with a mouth having a diameter

- larger than that of said outlet, means for vibrating said bottom and outlet in relation to said tube, and an inverted substantially funnel-shaped member disposed within said 5 hopper a substantial distance above said outlet.
4. In a device of the character described, the combination with a hopper having a perforated bottom provided with a tubular outlet, of a stationary tube leading from said outlet and provided with a mouth having a diameter larger than that of said outlet, means for vibrating said bottom and outlet in relation to said tube, and an inverted 10 substantially funnel-shaped member disposed within said hopper a substantial distance above said outlet.
5. In a device of the character described, the combination with a hopper having a 15 tubular outlet, of means for vibrating said outlet, and an inverted substantially funnel-shaped member disposed within said hopper a substantial distance above said outlet.
6. In a device of the character described, the combination with a hopper having a bottom provided with a tubular outlet, of means for vibrating said bottom and outlet, and an inverted substantially funnel-shaped member disposed within said 20 hopper a substantial distance above said outlet.
7. In a device of the character described, the combination with a hopper having a perforated bottom provided with a tubular outlet, of means for vibrating said bottom and outlet, and an inverted substantially funnel-shaped member disposed within said hopper a substantial distance above said 25 outlet.
8. In a device of the character described, the combination with a hopper having a concave bottom provided with a tubular outlet, of a stationary tube leading from said outlet and provided with a mouth having a diameter larger than that of said outlet, means for vibrating said bottom and outlet in relation to said tube, and an inverted substantially funnel-shaped member disposed within said 30 hopper a substantial distance above said outlet.
9. In a device of the character described, the combination with a hopper having a perforated concaved bottom provided with a tubular outlet, of means for vibrating said bottom and outlet, and an inverted substantially funnel-shaped member disposed within said hopper a substantial distance above said 35 outlet.
10. In a device of the character described, the combination with a hopper having a bottom provided with a tubular outlet and carrying lugs upon its upper face, of a stationary tube leading from said outlet and provided with a mouth having a diameter larger than that of said outlet, means for vibrating said bottom and outlet in relation to said tube, and an inverted substantially funnel-shaped member disposed within said hopper a substantial distance above 40 said outlet.
11. In a device of the character described, the combination with a hopper having an oscillatable bottom provided with an outlet, of a stationary tube leading from said outlet and provided with a mouth having a diameter larger than that of said outlet, means for oscillating said bottom in relation to said tube, and an inverted substantially funnel-shaped member disposed within said hopper a substantial distance above 45 said outlet.
12. In a device of the character described, the combination with a hopper having an oscillatable bottom provided with an outlet and carrying lugs upon its upper face, of a stationary tube leading from said outlet and provided with a mouth having a diameter larger than that of said outlet, and means for oscillating said bottom in relation to said tube.
13. In a device of the character described, the combination with a receptacle for a mass of sealing disks of cork or the like, and a chute to receive and stack the disks; of an intermediate reciprocatory plate provided with a circular opening sufficiently large to pass a disk and registering with said chute; and two diametrically-opposed members extending from the surface of said plate in proximity to said opening.
14. In a device of the character described, the combination with a receptacle for a mass of sealing disks of cork or the like, and a chute to receive and stack the disks; of an intermediate reciprocatory plate provided with a circular opening sufficiently large to pass a disk and registering with said chute; and two diametrically-opposed members in proximity to said opening, extending from said plate in a plane at right angles to the direction of movement thereof.

Signed at New York, in the county of Kings and State of New York, this 25th day of April, A. D. 1916.

JOHN BINDER.
EMILIO ALBERTI.
